UNITED STATES PATENT OFFICE.

JOHN ALEXANDER HOPE, OF MONTREAL, QUEBEC, CANADA.

JOURNAL-BOX JACK.

1,369,432.

Specification of Letters Patent. Patented Feb. 22, 1921.

Application filed October 22, 1919. Serial No. 332,566.

To all whom it may concern:

Be it known that I, JOHN A. HOPE, of the city of Montreal, Province of Quebec, Dominion of Canada, a subject of the King of Great Britain, have invented certain new and useful Improvements in Journal-Box Jacks; and I do hereby declare that the following is a full, clear, and exact description thereof.

10 Journal box jacks as heretofore known have for the most part taken two forms, neither of which is wholly satisfactory. The jack most commonly employed is an ordinary lifting jack which must be seated upon 15 a suitable support on the road bed beneath the journal box. Because of road or weather conditions it is frequently very difficult to properly support the jack and consequently much difficulty is experienced in removing 20 the wedge and brass from the journal box. Further it is necessary with such a jack that some auxiliary means be provided for holding 25 the journal against upward movement with the box and this increases the difficulty of using this jack. In the second form of 30 jack, which is not extensively used, the lifting member is suspended from the wheel. These jacks however, are necessarily more or less complex and bulky in their construction and are slow of operation.

The object of the present invention is to provide a journal box jack which will be simple in its construction and operation and which can be quickly and easily placed in 35 operative position, without regard to road bed or weather conditions and which when in position will not interfere with the removal of the wedge and brass.

In the accompanying drawings Figure 1 40 is a side elevation of a jack embodying my invention, showing the same applied to a journal; Fig. 2 is an end elevation of the same; Fig. 3 is a rear, or inner, view of the fulcrum block; Fig. 4 is an end elevation 45 of the fulcrum block; Fig. 5 is a transverse sectional view of fulcrum block taken on the line 5—5 of Fig. 6; Fig. 6 is an outer, or front, elevation of the fulcrum block; Fig. 7 is a plan view of the fulcrum block; Fig. 8 is a side elevation, partly in section, of the lower end of the jack; Fig. 9 is a sectional view taken on the line 9—9 of Fig. 11; Fig. 10 is a section taken on the line 10—10 of Fig. 8; Fig. 11 is a plan view of the lower

portion of the jack and the lifting member; 55 and Fig. 12 is a perspective detail view of one member of the fulcrum block.

In carrying out my invention I provide a jack having a part adapted to extend into the outer end of the journal box, through the 60 usual opening therein, and to rest upon the journal. Carried by this part is a lifting member which is arranged to be brought into lifting engagement with the journal box, or some part of the car structure connected therewith. Suitable means are provided for actuating the lifting member to cause the box to be elevated relatively to the journal. Inasmuch as the jack is supported wholly from the journal it will be obvious 65 that the condition of the road bed will in no way interfere with the use of the jack, and further that the weight of the load itself will hold the journal against upward movement with the box. Moreover, the construction is such that the whole mechanism may be arranged out of alignment with the wedge and brass which are to be removed, and will not in any way interfere with the removal 70 of these parts. In the accompanying drawings I have illustrated one embodiment of 75 my invention, which at the present time represents the preferred form of the jack, but it will be understood that the jack may take various forms, widely different from that 80 here illustrated, without departing from the spirit of my invention.

The preferred embodiment of my invention consists of a block 2 adapted to fit on the free end of the journal for the purpose 90 of fulcruming the main body of the jack thereon. This fulcrum block is of greater width than the diameter of the collar of the journal and consists of two sections 3 and 4 having overlapping portions 5 presenting a 95 flat inner face 90 adapted to bear against the outer face of the journal, said block having a horizontal socket 6 extending from side to side within which the jack proper is constructed and arranged to be fulcrumed. Each of the sections is tapered downwardly 100 as at 7 and is provided with a rearward projection 8 at each side edge. These projections are constructed and arranged to straddle the collar of the journal each being machined out to present channel 9 into which the collar projects when the block is fitted thereon. The block is divided into two sec-

tions in order that it may be adjusted to fit journals of different sizes, the overlapping portions 5 being fastened together by bolts 91 passing through borings 92 and slots 93 in the respective sections. The inner ends of these bolts are countersunk as at 94 to present a flat face for abutment with the journal end, and the opposite ends of the bolts project outwardly beyond the block 10 and are screw-threaded to receive nuts 95 between which and the block helical springs 96 bear. The purpose of these springs is to yieldingly maintain the teeth 97 on each of the overlapping portions in relative engagement. When the sections have been adjusted to fit a journal the nuts 95 are tightened.

The body member 10 of the jack which is fulcrumed in the block is of hook form reinforced by a rib 12 the upper end of which 20 is tapered off as at 13 to afford ample clearance for the removal of the wedge and journal bearing, the extreme end being rounded off as at 14 and seated in the socket 6 of the block. The lower end of the body member 25 is curved to extend beneath the journal box and is provided with an enlargement 15 containing a chamber 16.

The means for exerting jacking force upon the underside of the journal box is 30 carried by this lower end and consists of a jack screw 17 projecting upwardly through the chamber in a line intersecting a point in close proximity to the point of fulcrum of the jack and having a longitudinal 35 feather-way 18. Upon this screw and located within the chamber is a combined worm wheel and nut 19 which is internally screw-threaded for engagement with the threads of the jack screw while its periphery is gouged out as at 20 to intermesh with a worm 21. This worm is formed integrally with a stub shaft 22 journaled in a transverse boring 23 in position to intermesh with the combined worm wheel and nut. 40 In order to prevent displacement of the nut from its chamber and convert the torque of the nut into axial movement of the jack screw, a ring 24 encircling the jack screw closes the upper end of the chamber and is 45 provided with an inwardly projecting feather 25 which registers with the feather-way in the screw. The ring is mounted rigidly in place by means of a radial extension 26 seated in groove 27 in the adjacent 50 portion of the body and held in place by a screw 28. Ball races 30 are provided for both the combined worm wheel and nut and worm.

In order to permit of easy assembly and 60 inspection of the parts the boring 23 is of increased diameter as at 31 to permit of the insertion of the worm, the end of the widened portion being closed by a cap 32. This cap constitutes a bearing for one end of the 65 shaft 22 the opposite end of the shaft pro-

jecting outwardly from the body of the jack and having mounted thereon a ratchet mechanism for rotating the same. This ratchet mechanism, which may be of any desired construction, in the embodiment illustrated 70 consists of a housing 33, a ratchet wheel 34 mounted on the squared portion 35 of the shaft 22 and within the forked end of the housing, a pawl 36 fulcrumed as at 37 in the housing, a detent pin 38 with spring 75 39 for maintaining the pawl in position with one of its ends in engagement with the teeth of the ratchet wheel and an operating handle 40. The shaft 22 is extended outwardly beyond the ratchet wheel 34 and has mounted thereon a knob 41. The purpose of this knob is to provide means for obtaining a quick manual feed of the jack screw until it comes into engagement with the under side of the journal box at which point the handle is used.

In order to lubricate the jack screw and the parts in intimate intermeshing relation therewith, a cup 50 is screwed into the lower end of the jack directly beneath the chamber 90 16 and in communication therewith and this cup is filled with lubricant and adapted to receive the lower end of the jack screw.

To prevent the jack screw from slipping laterally when in engagement with the journal box, its upper end is provided with two shallow grooves 52 extending at right angles to each other and presenting flat teeth 53 these teeth engaging the box and acting as antiskids. The same result may be obtained, however, by serrating the top of the 95 jack screw.

To provide means for readily carrying the jack the rib 12 is provided with a hand-hole 75. It is to be distinctly understood that while I describe my improved jack as adapted to journal boxes, it may be equally well adapted to other purposes and although the embodiment illustrated is the one I prefer to use for journal box work, yet if desired the general construction may be varied, without departing from the spirit of my invention so long as it is hung from and fulcrumed on the free end of the journal.

Operation.

In using my improved jack the door of the journal box is swung open and the fulcrum block 3 fitted over the free end of the journal. The end 14 of the jack is then fulcrumed in this block in position with its opposite end extending beneath the underside of the journal box. The jack screw is then fed up into engagement with the box by means of the knob 41. At this point jacking 125 is effected by means of the handle 40 which is oscillated until the box is moved upwardly to an extent sufficiently to release the wedge and bearing and to permit these parts to be moved outwardly. The wedge and bearing 130

are then removed and replaced, after which the ratchet pawl 36 is disengaged from the ratchet wheel and the box returned to its normal position. The removal of the jack 5 completes the operation.

What I claim is as follows:

1. A journal box jack, one end of which is constructed and arranged to be fulcrumed upon the journal within the journal box and 10 the opposite end to bear upon the underside of the journal box.

2. A journal box jack having a member adapted to pivotally engage the end of the journal said jack being constructed and arranged to exert jacking force upon the bottom of the box in line with the fulcrum 15 point.

3. A journal box jack consisting of a fulcrum member adapted to fit on the end of the journal, a unitary body member one end 20 of which is constructed and arranged to fulcrum in said fulcrum member and means carried by the other end of said member and constructed and arranged to bear upon the 25 underside of the journal box for the purpose of exerting a jacking force thereon.

4. A journal box jack consisting of a fulcrum block adapted to fit on to the journal, said block having a socket therein, a body 30 of hook form the upper end of which is constructed and arranged to be fulcrumed in said socket with its lower end extending beneath the journal box, means carried by said lower end for exerting jacking force upon 35 the underside of the journal box said means consisting of a jack screw, a combined worm wheel and nut encircling said jack screw, means for preventing rotation of said jack screw and displacement of the combined 40 worm wheel and nut, a worm wheel in intermeshing relation with said combined worm wheel and nut, and manually operated means connected to said worm for rotating the same.

45 5. A journal box jack for assisting in the removal of the wedge and journal bearing, said jack being constructed and arranged to extend through the outer end wall of the journal box and to be suspended from the 50 journal and being wholly located below the horizontal plane of the wedge for the purpose of presenting an unobstructed path for the removal of the same.

60 6. A journal box jack consisting of a fulcrum block adapted to fit on to the journal, said block having a socket therein and having rearward projections adapted to straddle the journal, a body of hook form the upper end of which is constructed and arranged to be fulcrumed in said socket with its lower 65 end extending beneath the journal box, said body member being strengthened by a rib formed integrally therewith and having a hand-hole for carrying the jack and a chamber at its lower end, means carried by said

lower end for exerting jacking force upon the underside of the journal box, said means consisting of a jack screw the axial plane of which intersects a point in close proximity to the point of fulcrum of the jack, said jack 70 screw having a longitudinal feather-way, a combined worm wheel and nut located within said chamber and encircling the jack screw, means for preventing displacement of the nut and converting the torque of the 75 nut into axial movement of the jack screw said means consisting of a ring encircling said screw and rigidly secured to the body of the jack and having a feather registering with said feather-way; a boring within the 80 body of the jack adjacent said jack screw a portion of said boring being of increased diameter, a removable cap closing one end of said boring, a stub shaft journaled within said boring, a worm wheel rigidly mounted 85 upon said shaft, the latter projecting outwardly through the reduced end of said boring, ratchet means mounted upon said outwardly extending end and a manually operated knob mounted upon the extreme end 90 of the outwardly projecting portion of the shaft for the purpose of obtaining a quick feed of the jack screw, and means for lubricating the jack screw and parts in intermeshing relation therewith said means consisting of a cup carried by the lower end 95 of the jack and constructed and arranged to receive the lower end of the jack screw.

7. A journal box jack having a fulcrum member adapted to fit on to the end of the journal said fulcrum member being adjustable for the purpose of fitting journals of different sizes, said jack being constructed and arranged to exert jacking force upon the bottom of the box in line with the fulcrum 105 point.

8. A jack of the character described, comprising a part constructed and arranged to extend through the outer end wall of a journal box and to be suspended from the journal, a second part connected with the first mentioned part for movement relatively thereto and arranged to be brought into lifting engagement with the part which is to be raised, and means for imparting lifting movement to the last mentioned part. 110

9. A jack of the character described, comprising a part constructed and arranged to extend through the outer end wall of a journal box and to be supported solely by the 120 journal, a second part connected with the first mentioned part for movement relatively thereto and arranged to be brought into lifting engagement with the under side of the journal box, and means for imparting lifting movement to the last mentioned part. 125

10. A jack of the character described, comprising a body member having at one end a part to extend through the opening in the outer end of a journal box and to be 130

- supported by the journal and having at its other end a lifting member to engage the journal box, and means for actuating said lifting member.
- 5 11. A jack of the character described, comprising a C-shaped body member having its upper end arranged to enter a journal box and to be supported by the journal and having its lower end extending beneath said journal box, a lifting member carried by said lower end of said body member, and means for actuating said lifting member.
- 10 12. A jack of the character described, comprising a part constructed and arranged to extend through the outer end wall of a journal box and to be suspended from the journal, and an operable lifting member carried by said part and arranged to engage the part to be lifted.
- 15 13. In a jack of the character described, a device to be supported by the outer end of a journal, a body member formed separately from and supported by said device, a lifting member carried by said body member, and means to actuate said lifting member.
- 20 14. In a jack of the character described, a device to be supported by the outer end of a journal, a body member formed separately from and pivotally supported on said device, a lifting member carried by said body member, and means to actuate said lifting member.
- 25 15. In a jack of the character described, a device to be supported by the outer end of a journal, a body member supported by said device and constructed and arranged to extend through the opening in the outer end wall of the journal box, a lifting member carried by said body member, and means to actuate said lifting member.
- 30 16. In a jack of the character described, a device to be supported by the outer end of a journal, a body member pivotally supported on said device and constructed and arranged to extend through the opening in the outer end wall of the journal box, a lifting member carried by said body, and means to actuate said lifting member.
- 35 17. In a jack of the character described, a device to be supported by a journal, said device being adjustable to accommodate it to journals of different sizes, a body member supported by said device, a lifting member carried by said body member, and means to actuate said lifting member.
- 40 18. In a jack of the character described, a hook shaped part to engage over the flanged end of a journal, a body portion supported by said hook shaped part and arranged to extend through the outer end wall of the journal box, a lifting member carried
- by said body portion, and means for actuating said lifting member.
- 45 19. In a jack of the character described, a body member, means for supporting said body member on a journal, said means comprising two journal engaging parts adjustable relatively one to the other, a lifting member carried by said body member, and means to actuate said lifting member.
- 50 20. In a jack of the character described, a body member having a part constructed and arranged to extend through the opening in the outer end of a journal box and to be supported by the journal and having another part arranged to be positioned beneath the journal box, a screw threaded lifting member mounted in the last mentioned part of said body member, and means for actuating said screw.
- 55 21. In a jack of the character described, a body member having a part constructed and arranged to extend through the opening in the outer end of the journal box and to be supported by the journal and having another part arranged to be positioned beneath the journal box, a nut rotatably mounted in the last mentioned part of said body member and held against axial movement relatively thereto, a lifting member screw threaded into said nut, and means for rotating said nut.
- 60 22. In a jack of the character described, a body member having a part constructed and arranged to extend through the opening in the outer end of the journal box and to be supported by the journal, and having another part arranged to be positioned beneath the journal box, a nut rotatably mounted in the last mentioned part of said body member and held against axial movement relatively thereto, said nut having teeth on the outer periphery thereof, a worm mounted in said last mentioned part of said body member and meshing with the teeth on said nut, means for rotating said worm, and a lifting member screw threaded in said nut.
- 65 23. In a jack of the character described, a hook-shaped part to engage over the flanged end of a journal, a part separate from and supported by said hook-shaped part, and an operable load engaging member connected with the last mentioned part and arranged to engage the part to be lifted.
- 70 24. In testimony whereof I have signed my name to this specification in the presence of two witnesses.
- 75 25. JOHN ALEXANDER HOPE.
- 80 26. Witnesses:
- 85 GORDON G. COOKE,
WILLIAM J. C. HEWETSON.
